SIDE RAIL FOR VEHICLE FRAMES

Donald W. Sherman, Shorewood, Wis., assignor
to A. O. Smith Corporation, Milwaukee, Wis.,
a corporation of New York

Application November 30, 1936, Serial No. 113,341

2 Claims. (Cl. 280—106)

This invention relates to a side rail for vehicle frames. The invention has been applied to the reenforcing of the rear kick-up of the conventional sheet metal channel side rail.

5 The object of the invention is to increase the strength of the side rail at the rear kick-up, for the purpose of resisting vertical loads.

The invention is illustrated, in its preferred embodiment, in the accompanying drawing in 10 which:

Figure 1 is a perspective view of the rear kick-up of a side rail;

Fig. 2 is a transverse section on line 2—2 of Fig. 1;

15 Fig. 3 is a similar section showing conventional construction prior to the present invention; and

Fig. 4 is a perspective view of a frame embodying the invention.

The side rails of automobile frames are constructed of sheet metal bent into channel shape 20 and having a portion curved upwardly at or near the location of the rear axle. This curved portion is known as the rear kick-up and is usually of shallow vertical web in order to provide the necessary clearances.

25 Referring to the drawing, the channel side rail 1 is formed with a rear kick-up 2. The vertical web 3 of the side rail is of varying depth throughout its length, and is generally shallow 30 in the portion of the rear kick-up. This means that in forming the channel side rail, the sheet metal stock employed was trimmed to a narrower blank in the region of the rear kick-up than in regions forward thereof. This is particularly 35 true with the former conventional type of rear kick-up illustrated in Fig. 3. To compensate for the shallow side rail at the kick-up, as illustrated in Fig. 3, it was the practice to place a reenforcing channel 4 over the open side of the 40 channel 1 and rivet it to the upper and lower

flanges 5 and 6 of the channel, thereby forming a box-like structure.

The present invention utilizes more of the original stock at the rear kick-up and provides a reinforced structure having greater strength as 5 to vertical loads. Referring to Figs. 1 and 2, the main body of the side rail is formed as a channel 1 with a vertical web 3, as before, but the web 3 is bent inwardly in its central portion 7 at the rear kick-up, as shown in Fig. 2, thereby utilizing 10 more of the stock than heretofore. The reenforcing channel 8 is reversed in direction and inserted with its vertical web 9 riveted to the vertical web portion 7 of channel 1 by rivets 10. The upper and lower flanges 11 and 12 of channel 8 extend 15 outwardly adjacent the respective flanges 5 and 6 of channel 1 and are riveted thereto by rivets 13.

Fig. 4 shows an assembled frame in which two side rails 1 are connected by suitable cross bars 14. The rear kick-up 2 in each side rail embodies 20 the present invention.

The invention may have various embodiments within the spirit and scope of the claims.

I claim:

1. In an automobile frame, a side rail having a 25 rear kick-up formed of two channel shaped members nested together and having their respective corresponding flanges secured together and having the web of the outer member bent inwardly to engage the web of the inner member, and 30 means connecting said webs together.

2. In an automobile frame, a side rail having a rear kick-up formed of two channel shaped members nested together with their respective corresponding flanges secured together and having a space between the planes of their webs, the web of the outer member being formed inwardly to engage the web of the inner member approximately mid-way between the flanges, and 35 means connecting said webs together.

DONALD W. SHERMAN.
